UNITED STATES PATENT OFFICE.

CLAUDE E. BOWERS, OF LOS ANGELES, CALIFORNIA.

ANCHOR FOR SLEEPERS.

Application filed March 13, 1926. Serial No. 94,384.

This invention relates to a device for rigidly securing sleepers to concrete floor foundations in order that wood flooring may be readily secured thereto.

5 A main object of my invention is to provide a simple device in which the anchoring members are readily insertable in concrete before the same is set, and in which the sleeper attaching members are pivotally attached thereto, whereby the attaching members may be readily swung to a horizontal position in contact with the concrete foundation when not in use.

10 A further object is to provide a device in which the anchoring members may be readily adjusted to receive sleepers of varying widths.

15 A still further object is to provide a device that is of simple construction, and that may be formed of inexpensive materials.

20 Other objects and advantages will be apparent from the following description when taken in connection with the accompanying drawings forming a part thereof, in
25 which—

Fig. 1—is a cross section of a concrete floor showing a pair of sleeper anchors embedded therein, sleeper attaching members of one anchor being folded and the other anchor device secured to the sleeper.

30 Fig. 2—is an enlarged end elevation of an anchor device embedded in a concrete floor with a sleeper secured thereto, the dotted lines indicating the method of adjusting the anchor members for sleepers of greater dimensions.

35 Fig. 3—is a perspective view of one of the devices.

40 Fig. 4—is a side elevation of an anchor device with a sleeper attached thereto.

45 Referring to the drawings, and especially to the perspective view shown in Fig. 3, it will be seen that the anchoring device 5, is formed from a single length of wire bent into the form of an elongated closed loop, the ends of which are laterally bent into parallelism and constitute anchors 7 adapted to be embedded in a concrete floor 8. Hingedly secured to each of the intermediate portions 9, 10, of the anchoring members are sleeper attaching members 11, each preferably formed of galvanized sheet metal of a sufficiently heavy gauge to prevent accidental deformation, and bent upon itself to form a hinge bearing 12, in order that the attaching members may be swung into a

vertical or horizontal position, the latter position being desirable prior to the attachment of the sleeper members 13 thereto as when in such position they will offer no 60 obstructions to the passage of wheelbarrows thereon during construction operations. The two portions of the flat attaching members are secured together by spot welding, and each are provided with openings 15 for the passage of nails therethrough for securing the same to the sleepers.

65 In Fig. 2 the anchor device is shown on an enlarged scale attached to a sleeper, the distance between the intermediate portions 70 9, 10, of the loop anchoring member being substantially the same as the width of the sleeper 13 attached thereto. By securing the attaching members in this manner with the cylindrical hinge bearings 12 disposed 75 beyond the side faces of the sleeper the bottom face of the sleeper will rest upon the surface of the concrete floor or foundation.

80 Frequently the width of the sleepers used may be greater than the width between the attaching members, thus if the anchor devices were designed to carry two by four inch sleepers and it was desired to use three by four inch, the intermediate portions 9 and 10 may be readily stretched apart, as 85 clearly shown in dotted lines in Fig. 2, to receive such sleepers.

85 By forming the anchor members 7 in V-shaped form, it will be apparent that they may be readily inserted into the wet concrete, and further as space between the intermediate portions 9 and 10 is open, the concrete between the same may be quickly tamped, thus insuring a complete embedding of the anchor members, this feature 90 95 constituting one of the important advantages of the device.

What I claim is:

95 A sleeper anchor consisting of a single length of readily bendable wire bent into 100 the form of an elongated closed loop, the ends of said loop being bent at right angles in parallelism, and a flat sheet metal sleeper attaching plate movably secured to each of the side members of the loop, the side members 105 adapted to be moved to or from each other, whereby the distance between the attaching members may be quickly adjusted.

110 In witness that I claim the foregoing I have hereunto subscribed my name this 10th day of February, 1926.

CLAUDE E. BOWERS.
